DES. 1994

Charles Yenner, of Cincinnati, Ohio,
Assignor to

M. Greenwood & Co. of the same place.

Letters Patent No. 1994. Dated Oct 18, 1864.

Design for a Shore and Tongue Stand.

The schedule referred to in these Letters Patent and making part of the same.

To all whom it may concern:

Be it known that Charles Yenner, of Cincinnati, Hamilton County, Ohio, have invented and produced a new ornamental design for a shore and tongue stand, represented in the accompanying drawings, making a part of this specification and in which

Fig. 1 is a front elevation of those parts of the stand which are above the base.

Fig. 2 is a top view of the base.

Fig. 3 is a top view of the branches.

I claim. The represented design for a shore and tongue stand.

On the testimony of which invention I hereunto set my hand,

Witnesses:

Geo. H. Knight
P. Y. Brown.

Charles Yenner.
